UNITED STATES PATENT OFFICE.

ROBERT WILLIAM SHAW, OF STAMFORD, CONNECTICUT.

PROPELLER-WHEEL.

No. 870,136.

Specification of Letters Patent.

Patented Nov. 5, 1907.

Application filed September 15, 1906. Serial No. 334,723.

To all whom it may concern:

Be it known that I, ROBERT WILLIAM SHAW, a citizen of the United States, residing at Stamford, in the county of Fairfield and State of Connecticut, have invented a new and useful Propeller-Wheel, of which the following is a specification.

This invention relates to screw propellers for motor propelled boats and its object is to provide a device of this character made up of sections which may be separately replaced in event of breakage.

A still further object is to provide propeller blades which are so shaped as to produce the maximum propelling force with the minimum power and which will not slip within the water.

Another object is to provide a propeller which is so constructed that it will not drag the stern of the boat downward but will insure the boat remaining on an even keel throughout the operation of the propeller.

It is a well known fact that where flat propeller blades are employed there is considerable radial motion of the water produced thereby which results in a corresponding diminution of power. Moreover this radial motion results in a downward pull upon the stern of the boat.

The object of the present invention is to provide a propeller which will overcome all of these objections and will neither produce radial movement of the water, nor drag the stern of the boat.

With the above and other objects in view the invention consists of certain novel features of construction and combinations of parts which will be hereinafter more fully described and pointed out in the claims.

In the accompanying drawings is shown the preferred form of the invention.

In said drawings: Figure 1 is a view partly in side elevation and partly in section of a propeller constructed in accordance with the present invention; and Fig. 2 is an end elevation thereof.

Referring to the figures by characters of reference, 1 is a propeller shaft upon which is arranged a hub 2 made up of similarly disposed sections adapted to embrace the shaft, the ends of said sections when brought together forming frusto-conical extensions 3 which are externally screw-threaded as shown at hand adapted to receive a frusto-conical nut 5 having 4 tapered, threaded opening therethrough. Extending from each section of the hub is a blade 6 of peculiar contour and the inner or base portion 7 of the blade is disposed diag-

onally upon the hub section and said blade is inclined backward over the adjoining end of the shaft 1 so as to form a wing which overhangs one of the nuts 5. The 50 blade is curved transversely so that the convex or advancing edge 8 thereof will cut into the water and cause the concave face of the blade to constantly press against the water. It will be understood that both blades are of the same contour. After the blades have been assembled by clamping the hub sections upon the shaft 1 the same are rotated in the usual manner and the convex edges thereof first contact with the water and as the rear or working faces of the blade are concaved transversely it will be understood that the water is positively 60 propelled longitudinally of the device and there is no radial motion and no slipping of the blades such as occurs where flat diagonally disposed blades are used. The curved blades such as herein described continually exert a pressure upon the water because of the constantly changing contour thereof. A propeller such as herein described will not pull downward on the stern of the boat and therefore said boat will be made to more quickly respond to the rudder. The sections of the propeller can be easily removed from the shaft in the event 70 of breakage and others substituted therefor.

The preferred form of the invention has been set forth in the foregoing description but I do not limit myself thereto as I am aware that modification may be made therein without departing from the spirit or sacrificing 75 the advantages thereof, and I therefore reserve the right to make such changes as fairly fall within the scope of the claims.

What is claimed is:

1. A propeller comprising a sectional hub, means upon 80 the ends of the sections for clamping the same upon a shaft, and outwardly inclined blades disposed diagonally to the axis of the hub, each blade being concavo-convex in cross section.

2. A propeller comprising a sectional hub, the ends of 85 said sections being tapered and screw-threaded, means engaging the threaded ends of the sections for clamping the same upon a shaft, and outwardly inclined blades disposed diagonally to the axis of the hub, each blade being concavo-convex in section.

In testimony that I claim the foregoing as my own, I have hereto affixed my signature in the presence of two witnesses.

ROBERT WILLIAM SHAW.
